UNITED STATES PATENT OFFICE.

ALEXANDER L. SCHRAM, OF HILLSBORO, ILLINOIS, ASSIGNOR TO SCHRAM GLASS MANUFACTURING COMPANY, OF ST. LOUIS, MISSOURI, A CORPORATION OF MISSOURI.

LUBRICATOR FOR SHEET METAL.

1,206,146.

Specification of Letters Patent. Patented Nov. 28, 1916.

Application filed October 6, 1914. Serial No. 865,295.

To all whom it may concern:

Be it known that I, ALEXANDER L. SCHRAM, a citizen of the United States, and resident of Hillsboro, Montgomery county, 5 Illinois, have invented certain new and useful Improvements in Lubricators for Sheet Metal, of which the following is a specification containing a full, clear, and exact description, reference being had to the accompanying drawings, forming a part hereof.

My invention relates to improvements in lubricators for sheet metal, in which there is a container for a fluid body of lubricant, having therein a support for a roll of sheet metal, means for unwinding the roll and causing its unwound portion to be passed through the lubricant and which means acts to carry the lubricated sheet to a machine to act on the sheet metal, and a means for 20 "wiping" the sheet so that a surplusage of lubricant is not carried away from the container.

The principal object of my invention is to construct a simple and inexpensive device for automatically feeding a press or other machine a sheet of material supplied with lubricant in order to facilitate the operation of the machine in its action on the material, and in order that the act of lubricating the material may be economically accomplished, both as to quantity of lubricant and operator's time.

With the above purposes in view, my invention consists in certain novel details of construction which will be fully set forth in my specification, pointed out in my claims and illustrated by the accompanying drawings, in which:

Figure 1 shows in plan a machine embodying my invention; Fig. 2 is a simple, longitudinal sectional elevation; and Fig. 3 is a simple, transverse sectional elevation of the machine.

Referring by numerals to the accompanying drawings: 5 designates a hollow standard carrying at its top a clamping ring 6. This hollow standard and clamping ring provide a vertically adjustable support for a post 7, having at its upper end an elbow 8 terminating in a circular plate 9 provided with a centrally disposed internally threaded bore and a pair of concentrically arranged slots 10.

The numeral 11 designates an open topped

tank, adapted to contain a body of fluid 55 lubricant, which is provided in its bottom with a screw plug 12 for drawing off the lubricant when desired.

Removably positioned within the tank is a rack comprising cheek plates 13, and a plurality of rollers 14 in arcual arrangement, extending transversely of the tank.

The two longitudinal or side walls of the tank extend at one end beyond the tank, and have their lowermost margins connected by 65 a drain board 15, located in a plane above the normal level of lubricant within the tank 5 and which drain board inclines toward the tank. These extended side walls over the drain board 15 have greater 70 heights than the side walls of the tank proper and in said walls are the open topped slots 16 in which are mounted the shafts 17 and 18. Located in the slots and bearing on said shafts are the followers 19 and secured to the upper margins of the side walls spanning said slots are the bridge-bars 20, each having internally threaded vertical bores arranged to receive the screws 21 which bear on the followers 19. 80

Mounted in the extended portions of the walls of the tank beneath the shaft 17 is a shaft 22, and secured to rotate with the shaft 22 is a unit comprising a bevel-gear wheel 23 and a spur-gear wheel 24. The spur-gear 85 wheel 24 is arranged to mesh with a spur-gear wheel 25 secured to rotate with the shaft 17.

Extended longitudinally of the tank and supported in bearings 26, carried by the tank 90 is a shaft 27 driven from a source of power (not shown) and carrying a bevel-gear wheel 28. The shafts 17 and 22 each carry a roller such as 29 and 30, which coact to move a sheet of material such as 31 taken from a 95 roll such as 32 supported in the body of lubricant in the tank 11 on the rollers 14.

Located between the roll 32 and the feed rollers 29 and 30 is a fixed wiper 33, over which the sheet 31 is drawn, and arranged 100 above the fixed wiper is a shaft 34, on which is pivotally mounted a rocker 35 having at its free margin a wiper 36, extending the width of the tank over the fixed wiper 33.

Carried by the rocker 35 is an arm 37, 105 upon which is slidably mounted a weight 38 carrying a set screw 39, whereby the weight may be held in different set posi-

- tions lengthwise of said arm to provide for variable pressures between the wipers as required to supply the sheet of material with a thick or thin film of lubricant, as desired.
- 5   Mounted on the shaft 18 is a roller 40, and in a plane beneath but not vertically alining therewith is a roller 41. These two rollers 40 and 41 coöperate with the feed rollers 29 and 30 to remove the "curl" from 10 the material drawn from the roll 32.
- Extending laterally from the tank is an arm 42 terminating in a semi-circle of the same radius as the plate 9, and which arm is perforated to receive a pin 43 having a 15 threaded stem which seats in the threaded bore, referred to, in the plate 10. On either side of the pin and carried by the arm 42 is a pair of cap screws 44, which extend through the slots 10 and seat in the arm 42.
- 20   By reason of the hollow standard, the post 7 and the clamping ring 6, I provide a means whereby the lubricating device may be altitudinally adjusted to adapt it for use in connection with machines such as presses whose 25 tables or beds are of different heights, and the pivotal connection between the post 7

and the tank 11 provides for an angular adjustment to adapt the lubricator to machines whose lines of functionate operations are other than vertical.

Having thus described my invention, what I claim as new therein and desire to secure by Letters-Patent of the United States therefor, is:

In a machine of the class described, a tank, a 35 drain board, a plurality of rollers in the tank for the support of a roll of sheet material, a pair of power driven rollers for moving the sheet material, a variable pressure gravity operated wiper and a pair of rollers in 40 staggered relationship with each other for removing the curl from the sheet material and means for adjusting one of said rollers relative to the other.

In testimony whereof, I have signed my 45 name to this specification, in presence of two subscribing witnesses.

ALEXANDER L. SCHRAM.

Witnesses:

E. L. WALLACE,
EDWARD E. LONGAN.
